(57) **CLAIM**

The ornamental design for a stimulator for medical use, as shown and described.

DESCRIPTION

FIG. 1 is a front, bottom perspective view of a stimulator for medical use, showing the new design;

FIG. 2 a front, bottom perspective view in a first configuration thereof;

FIG. 3 a front, bottom perspective view shown in a second configuration thereof;

FIG. 4 is a bottom plan view of the stimulator for medical use of FIG. 1;

FIG. 5 is a top plan view thereof;

FIG. 6 is a left-side elevation view thereof, with the right-side elevation view being a mirror image thereof;

FIG. 7 is a front elevation view thereof; and,

FIG. 8 is a front elevation view of the stimulator for medical use of FIG. 1, shown in a condition of use for clarity of the disclosure.

In the drawings, the broken lines depict environmental subject matter and forms no part of the claimed design.

1 Claim, 8 Drawing Sheets
